UNITED STATES PATENT OFFICE.

CHARLES M. BRADLEY, OF HARVEY, ILLINOIS, ASSIGNOR, OF ONE-HALF TO JAMES B. ELLIS, OF HARVEY, ILLINOIS.

ROTARY VALVE FOR INTERNAL-COMBUSTION ENGINES.

1,229,405.

Specification of Letters Patent. Patented June 12, 1917.

Application filed December 19, 1914. Serial No. 378,062.

To all whom it may concern:

Be it known that I, CHARLES M. BRADLEY, a citizen of the United States of America, and a resident of Harvey, county of Cook, 5 and State of Illinois, have invented certain new and useful Improvements in Rotary Valves for Internal-Combustion Engines, of which the following is a specification.

The main objects of this invention are to 10 provide an improved form of rotary valve and valve seat for internal combustion engines, adapted to coact to control both the inlet and the exhaust of the respective cylinders of the engine; to provide an improved arrangement of said valve and valve seat with 15 respect to the engine cylinder whereby the cooling fluid is caused to circulate around said parts in such manner as to insure a substantially uniform temperature of the valve 20 and valve seat whereby the expansion or contraction thereof is practically the same; to provide improved means for allowing for the escape of steam which may be formed in the water-jacket around said valve and valve 25 seat; to provide improved packing means for said valve to prevent leakage of the cooling fluid into the engine cylinder; to provide improved means for diverting from the engine cylinder any seepage that may pass said 30 packing means when the same becomes worn; and to provide an improved manner of lubricating said valve.

An illustrative embodiment of this invention is shown in the accompanying drawings, in which—

Figure 1 is a sectional elevation of the device as applied to a 4-cylinder internal combustion engine.

Fig. 2 is a detail partly sectional of the 40. valve.

Fig. 3 is a transverse sectional elevation taken on the line A—A of Fig. 1.

Fig. 4 is an end elevation taken from the 45. left of Fig. 1, part of the gear casing being broken away to more clearly illustrate the gearing by which the valve is rotated.

Figs. 5 and 6 are respectively sectional and end detail views of the packing glands.

In the construction shown in the drawings, the valve 1 is in the form of a hollow cylindrical element rotatably mounted in a valve seat formed in the casing 7. Peripheral depressions or passages 2 are formed in the valve 1 at intervals along its length and are adapted, during the rotation of the

valve, to successively open communication between the inlet and exhaust ports and the respective cylinders.

The casing 7 in which the valve 1 is journaled is herein shown as an integral part 60 of the cylinder heads of the cylinders C¹, C², C³ and C⁴. Inlet ports 21 and exhaust ports 22 are formed in the casing 7 at opposite sides of the valve 1, and are successively brought into communication with 65 the respective ports 19 through registration therewith of the valve passages 2. Thus the inflowing and outflowing gases come into contact with the same surfaces of the valve 1, namely, the walls of the passages 2. The 70 advantages of this are two-fold; the incoming fuel contacting with the heated surface of the passages 2 is more readily converted into a gaseous form at a temperature that will facilitate the ignition thereof; also this 75 action of the incoming fuel will tend to cool the heated part of the valve.

An inlet manifold 30 and the exhaust manifold 28 are arranged to communicate with the inlet and exhaust ports 21 and 22 80 respectively.

The driving mechanism for rotating the valve comprises a sprocket 14 secured by a key 26 to the valve 1 at one end thereof and connected by suitable sprocket chains 31 to 85 the crank shaft of the engine. The sprockets which are connected by the chains 31 are of such sizes as will give the necessary relative rotation of the valve with respect to the crank shaft for properly opening 90 and closing the ports. A casing of separable parts 17 and 18 surrounds the sprocket 14, and serves as a bearing for the adjacent end of the valve 1. The casing is preferably made of light material, such as aluminum, 95 and a suitable bushing 15 is therefore set in the part 17 of the sprocket housing to serve as a bearing for the valve. The part 17 of the sprocket housing is shaped to form the outlet 27 for the cooling fluid, a 100 hose or other connection being secured thereto for connecting with the radiator. The cooling of the valve 1 and valve casing 7 is accomplished by circulating water around and through the valve. For this purpose a 105 water-jacket 13 is formed in the casing 7 surrounding the valve 1 at all points between the ports 19, 21 and 22, and is in direct communication with the water-jacket 13^a of cylinders C¹, C², C³ and C⁴. The 110

valve 1 terminates inwardly of the ends of the casing 7, and the sprocket housing 17, and serves as the only outlet for the cooling fluid in its passage from the water-jacket 13 to the outlet 27 leading back to the source of supply. The water enters the valve from the water-jacket 13 through the end 5 and passes out through the end 6 into the outlet passage 27. The communication with the inlet end 5 and the valve 1 is indicated by dotted lines at the right hand end of Fig. 1. The cooling fluid is taken into the lower part of the cylinder water-jacket 13^a either by the thermo-siphon method or by pump, and as it becomes heated finds its way to the top of the water-jacket 13 in the valve casing 7. By reason of the fact that there is no other outlet for the water, it passes from the jacket 13 into the end 5 of the valve 1, passing therethrough into the discharge passage 27. Thus the water circulating in the water-jacket 13 and through the valve 1 is at substantially the same temperature so that the expansion or contraction of the valve is at all times substantially the same as that of the valve casing, thereby maintaining the fit of the valve in its seat. Any other course for the cooling water would not accomplish this result.

In other forms of engines, steam accumulating in the upper parts of the water-jacket and for the escape of which no special means are provided, must pass out through the fluid outlet in the same course that the fluid does. This usually results in a crackling and rumbling noise in the water-jacket. In the device herein shown this is overcome by forming a small duct or orifice 16 in the sprocket casing 18 connecting the highest point of the water-jacket directly with the fluid outlet 27. This orifice is very small in cross-sectional area (from $\frac{1}{16}$ " to $\frac{1}{8}$ " in diameter) and although at low temperatures, water will flow out therethrough, yet at high temperatures any steam forming in the upper part of the jacket 13 may readily escape without affecting the flow of the fluid through its regular path. In a construction of this kind, where it is absolutely essential to have the water flow from the valve casing through the valve in a steady uninterrupted stream of maximum volume in order to insure uniform cooling of the casing and valve, this provision of allowing for the escape of steam insures against the formation of steam pockets in the jacket of the valve casing or in the valve, which would interfere with the flow of water and result in an uneven cooling of the valve and its casing.

The arrangement of the valve hereinbefore described involves the necessity of packing the same so as to prevent the leakage of the cooling fluid into the cylinders. This is accomplished by means of packing glands 3—3^a threaded externally so as to be

screwed into the ends of valve 1 and having annular flanges fitting the valve seat and between which and the ends of the valve packing rings 4—4^a are compressed. The opposed faces of the valve ends and flanges are tapered so as to urge the packing outwardly against the valve casing. The packing glands are provided with hexagonal openings adapted to receive a suitable wrench by which they may be tightened or loosened, as occasion may require.

In order to further insure against the leakage of the cooling fluid into the cylinders, an annular groove 8—8^a is formed in the valve casing 7 adjacent to the ends of the valve 1, but inwardly of the packing rings 4—4^a and from which ducts 12—12^a lead to the exterior of the casing. Should there be any seepage of cooling fluid past the packing rings 4—4^a due to their becoming worn, it would be arrested by the grooves 8—8^a and directed by the ducts 12—12^a to the exterior of the engine casing. The annular grooves 8—8^a are partly incomplete near their upper portion so as to leave bearing surfaces along the whole surface of the valve to prevent the deposit from the cooling liquid increasing the size of the valve 1, and thereby interfering with its removal. The trickling of water from the ducts 12—12^a would be a signal that the packing glands need tightening.

A flange or ridge 9 is formed in the casing 7 above and along the valve 1 opposite the openings 19, and is provided with a key-hole shaped slot 9^a (Fig. 3) extending the entire length thereof, which forms a part of the means for lubricating the valve 1. The circular part of the key-hole shaped slot 9^a is continuous throughout its length, but the lower part is interrupted by obstructions 10 integrally formed with the casing 7 directly above the ports 19 in position to register with and cover the passages 2. These obstructions prevent communication between the key-hole shaped slot 9^a and either the inlet ports 21 and exhaust ports 22, which in the former case would cause a quantity of lubricating oil to be admitted to the inlet ports 21 and then be drawn into the cylinders, and which in the latter case would allow some of the exhaust gases to be admitted to the key-hole shaped slot and to find their way with considerable pressure into the upper part of the oil slot and to escape through other passages 2 simultaneously registering with the slot. In either case the quality of the fuel mixture would be deteriorated to a greater or less extent. By virtue of the obstructions 10 pockets are formed in the lower part of the slot 9^a, which are capable of confining a quantity of the lubricant so that in case the engine is maintained in an inclined position for a considerable period of time during its operation, the

oil will not be allowed to all run to one end of the valve. To insure a more equal distribution of the oil, the lower part of the slot 9^a between the obstructions may be 5 loosely packed with asbestos or other suitable packing. A plurality of threaded apertures 11 are located in the casing 7 directly above the obstructions 10, to which may be connected means for supplying the lubricant. This arrangement of oil slot 10 with a plurality of feed ducts insures a more uniform distribution of the lubricant over the entire surface of the valve.

The openings 20 in the rear wall of the 15 water jacket and 20^a in chain housing cover are closed by means of plates 24-24^a and plugs 25-25^a secured therein. The plugs 25-25^a are adapted to be removed when it is desired to insert a wrench for tightening the glands 3-3^a. When it is desired to remove packing glands entirely, it is necessary to remove the plates 24-24^a.

Although but one specific embodiment of 25 this invention has been herein shown and described, it will be understood that some of the details of the construction shown may be altered or omitted without departing from the spirit of this invention as defined by the following claims.

30 I claim:

1. In an internal combustion engine, the combination of a plurality of cylinders, a valve casing extending across said cylinders and having ports communicating with each 35 of said cylinders and adapted for the admission of gases to and the discharge thereof from said cylinders and having other ports leading respectively to inlet and exhaust passages, and a cylindrical valve rotatably mounted in said casing and having 40 passages formed therein arranged to register with said ports so as to successively open communication between said cylinders and the respective inlet and exhaust passages, 45 said casing having a longitudinally disposed oil passage extending substantially throughout the length thereof and having slots elongated in the direction of said oil passage and providing communication between said passage and the periphery of 50 said valve substantially throughout that part of the valve which is intermediate said valve passages, said casing also having a plurality of oil supply ducts connecting 55 with said oil passage at points intermediate said elongated slots through each of which oil is adapted to be continuously supplied to said passage.

2. In an internal combustion engine, the 60 combination of a plurality of cylinders, a valve casing extending across said cylinders and having ports communicating with each of said cylinders and adapted for the admission of gases to and the discharge thereof from said cylinders and having other

ports leading respectively to inlet and exhaust passages, a cylindrical valve rotatably mounted in said casing and having passages formed therein arranged to register with said ports so as to successively open 70 communication between said cylinders and the respective inlet and exhaust passages, and a ridge formed along the top of said valve casing and having an oil passage formed therein extending substantially 75 throughout the length of said valve and having slots elongated in the direction of said oil passage and providing communication between said passage and the periphery of said valve substantially throughout that 80 part of the valve which is intermediate said valve passages, the parts of said casing which separate said elongated slots providing obstructions covering said valve passages, said elongated slots being adapted to 85 retain packing therein, said ridge having a plurality of transverse oil supply ducts connecting with said passage at points located above said obstructions through each of which oil is adapted to be continuously supplied to said oil passage.

3. In an internal combustion engine, the combination of a cylinder, a valve casing having separate inlet and exhaust ports and a common port for the admission of gases 95 to and the discharge thereof from the cylinder, a hollow cylindrical valve rotatably mounted in said casing and having a passage formed therein adapted to successively open communication between said common 100 port and said inlet and exhaust ports, a water jacket surrounding said valve casing and communicating with the water jacket of said cylinder, said cylindrical valve communicating at one end with the water jacket 105 of said valve casing and forming the outlet passage for the cooling fluid, and means for packing the ends of said valve for preventing the leakage of cooling fluid from said water jacket into said engine cylinders, said 110 casing having grooves formed therein inwardly of said packing means and having a duct leading therefrom to the outside whereby any seepage of cooling fluid through said packing is drained away.

4. In an internal combustion engine, the combination of a cylinder, a valve casing having separate inlet and exhaust ports and a common port for the admission of gases to and the discharge thereof from the cylinder, a hollow cylindrical valve rotatably mounted in said casing and having a passage formed therein adapted to successively open communication between said common port and said inlet and exhaust ports, a 125 water jacket surrounding said valve casing and communicating with the water jacket of said cylinder, said cylindrical valve communicating at one end with the water jacket 130 and forming the outlet passage for the cool-

ing fluid, packing glands threaded externally so as to screw into said valve, an annular flange on said glands adapted to fit into the adjacent part of said valve casing and engage packing between said flange and the end of said valve, said water jacket having openings in the rear wall thereof in alignment with said valve seat through which said glands are adapted to be inserted or removed, plates for closing said

openings, and plugs threaded into said plates and adapted to be removed to permit said glands to be reached for adjustment.

Signed at Chicago this 16 day of Dec. 1914.
